EXERCISING APPLIANCE

John M. Thomson and John F. Mulhern,
New York, N. Y.

Application April 8, 1933, Serial No. 665,128

9 Claims. (Cl. 272—57)

This invention relates to exercising devices, and more particularly, to a device or appliance for exercising the feet and legs, or massaging or manipulating the bones of the feet.

5 An important feature of the present invention is the provision of an appliance on which the user may stand, and by the simple act of rocking from the heels to the toes not only exercise the muscles of the feet and legs but also, by applying pressure to the arch and metatarsal arch, tend to restore the positions of the bones in the vicinities of these arches to their natural and proper positions, and, at the same time by such movements and manipulations, remove lime or chalky deposits gathered on the metatarsals, the phalanges, and the bones adjoining the middle cuneiform.

The appliance of the present invention is intended to correct fallen arches, strengthen the bony structure of the foot, and build and strengthen leg and foot muscles. The proper use of the appliance of the present invention creates grace and ease in walking and improves posture and carriage of the body. The exercise of the leg and foot and manipulation of the foot bones tend 20 to eliminate stiffness, pains and aches, and also other bodily disorders resulting from chalky or lime deposits on the bony structures of the foot.

In the form at present preferred, the appliance of the present invention comprises a base portion 30 and two pairs of mounds or domes arranged on the base in parallel form, the base and mounds being formed preferably of sponge rubber. One mound of each set is substantially larger than the other and it is intended that the user's feet be placed on the appliance so that a large mound is directly under the arch of each foot. The smaller mounds are spaced from the larger ones at such a distance that they will be engaged by the metatarsal arches. The base is provided with portions 35 at the front and rear to be engaged by the toes and heels of the user when the feet are rocked in the manner referred to below in the use of the device.

Other features and advantages will hereinafter 40 appear.

In the accompanying drawing—

Figure 1 is a top plan view of the appliance of this invention.

Fig. 2 is a side elevation.

50 Fig. 3 is a sectional view taken through one pair of mounds.

Fig. 4 is a sectional view showing a modification of the mound shown in the other views.

55 Fig. 5 is a side elevation of the appliance, showing the bones of the user's foot in the position the

foot assumes when rocking forward on the metatarsal arch mound.

Fig. 6 is a view similar to Fig. 5, but showing the foot in the position rocking backward on the arch mound.

Fig. 7 is a plan view, showing the positions of the mounds laterally relative to the foot bones.

The appliance of the present invention, in the form shown in the accompanying drawing, comprises a base 10 which is preferably made of resilient material such as sponge rubber. On this base there are provided mounds 11, 12, 13 and 14. The mounds 11 and 12 form one pair and the mounds 13 and 14 form the other pair, and the pairs are arranged in parallel rows as shown.

These mounds are also preferably made of sponge rubber. The front of the base has a margin 15 between the mounds 12 and 14 and the front edge of the base, and the back of the base has portions 16 behind the mounds 11 and 13.

In use, the appliance is intended to be placed on the floor so that the user may stand upon the appliance with each foot over one pair of mounds with the heels of his feet in the margin 16 which, as shown in Fig. 1, may be extended beyond the rear edge 17 so as to assist the user in properly placing his feet on the mounds. When this is done, the mounds 11 and 13 will be located directly under the arch A while the mounds 12 and 14 will be located directly under the metatarsal arch M, and the mounds 11—12 and 13—14 will be on the longitudinal axes of the feet respectively.

In order that this condition may be obtained for feet of different lengths, the mounds 12 and 14 are made adjustable relative to the base 10. For this purpose, each of the mounds 12 and 14 is provided with a plug 18 which may be placed in one of a series of holes 19 at different distances from the rear mounds 11 and 13. The latter may also be made separate from the base 10 if desired and may be adjustable, but, since adjustment of the front mounds is sufficient, it is preferable that the rear mounds 11 and 13 be integral, cemented, or otherwise secured to the base 10.

The mounds 11 and 13 are substantially larger than the mounds 12 and 14, and this provision is made because the bones of the arch are much larger and stronger than the bones of the metatarsal arch.

The appliance is intended to be used as follows. After the user has placed his feet on the appliance so that the larger mounds 11 and 13 are located under the arches of his feet, the user shifts his weight forward so as to "stand on his toes", and, of course, at the same time lifting his heels and

5 arches upwardly and off the mounds 11 and 13, as shown in Fig. 5. In rocking forwardly, his weight is applied largely on the front mounds 12 and 14 which, as a result, mushroom somewhat, but nevertheless are resistant enough to press upwardly against the phalange and metatarsal joints. This pressure at these points on the metatarsal arch tends to spread the bones, not only exercising the muscles and tissues holding the bones together 10 but also permitting the bones to realign themselves in their natural and intended order.

15 Then the user rocks backwardly taking his weight off the toes and transferring it to the heels. In doing so, the user's weight is shifted to the large mounds 11 and 13 as shown in Fig. 6 which, being under compression, spread somewhat but nevertheless exert a reaction or upward pressure on the middle cuneiform MC and bones adjoining the same, including especially the scaphoid S. 20 This pressure on the arch, as with the metatarsal arch, causes the bones to be spread giving them an opportunity to realign themselves in the natural way, and, at the same time, also exercises and stimulates the muscles and tissues around these bones.

25 The person using the appliance continues rocking back and forth placing his weight first on the heels and then on the toes so long as not fatigued by the exercise.

30 The spreading or mushrooming of the mounds massages and manipulates the tissues of the foot under the arches and the pressure applied tends to remove the lime or chalky deposits which gather on the joints of the arch bones.

35 In addition to exercising and manipulating the foot, the rocking to and fro on the mounds also exercises and stimulates the tibia, fibula, and pelvis joints and the muscles controlling the same.

40 The appliance and the exercise above referred to may be employed either alone or with other exercises such as bending at the waist simultaneously with the shifting of the weight from the heels to the toes and/or the raising and swinging of the arms.

45 If more pressure is desired than that which would be produced by the sponge rubber of a texture satisfactory for the base, the mounds may be made with a cylindrical bore as shown in Fig. 4, and a spring 20 or other resilient member may be 50 inserted in this bore. When this is done, the upper end of the spring should have a cap 21 fitting the inner end of the bore while the lower end may be supported on a disk 22 and all the metal or extra parts held in the bore by a plug 23 of rubber or the like.

55 The base 10 may, of course, be made of material other than the material of which the mounds are made, but it is preferable that it be made of sponge rubber so that when rocking back on the heel, the oscalsis will be cushioned.

60 In connection with Figs. 5 and 6, it should be understood that these show substantially the terminal positions of the foot's movement. During the movement between these positions, greater weight is applied to the mounds and they are substantially flattened at times.

65 Other variations and modifications may be made within the scope of this invention and portions of the improvements may be used without others.

70 Having thus described the invention, what is claimed as new and for which it is desired to obtain Letters Patent, is:—

75 1. A foot exercising appliance comprising a base; and two pairs of mounds rising from and

fixedly mounted on the base, each pair being adapted to receive and support a human foot, the mounds of each pair being spaced from each other to respectively engage the arch and the metatarsal arch of the foot, said mounds being dome-shaped and being adapted to engage the foot on the longitudinal axis thereof. 80

2. A foot exercising appliance comprising a base; and two pairs of mounds rising from and fixedly mounted on the base, each pair being adapted to receive and support a human foot, the mounds of each pair being spaced from each other to respectively engage the arch and the metatarsal arch of the foot, the mound which engages the metatarsal arch being dome-shaped and in engagement with the foot in the vicinity of the second phalange and metatarsal joint tending to spread the phalange and metatarsal joints when the weight of the user is applied to the fore part of the foot. 85

3. A foot exercising appliance comprising a base; and two pairs of mounds rising from and fixedly mounted on the base, each pair being adapted to receive and support a human foot, the mounds of each pair being spaced from each other to respectively engage the arch and the metatarsal arch of the foot, the mound which engages the arch being dome-shaped and in engagement with the foot in the vicinity of the scaphoid bringing pressure to bear on the bones adjoining the middle cuneiform when the weight of the user is applied to the fore part of the foot. 90

4. A foot exercising appliance comprising a base; and two pairs of mounds rising from and fixedly mounted on the base, each pair being adapted to receive and support a human foot, the mounds of each pair being spaced from each other to respectively engage the arch and the metatarsal arch of the foot, the mound which engages the metatarsal arch being dome-shaped and in engagement with the foot in the vicinity of the second phalange and metatarsal joint tending to spread the phalange and metatarsal joints when the weight of the user is applied to the fore part of the foot and the mound which engages the arch being dome-shaped and in engagement with the foot in the vicinity of the scaphoid bringing pressure to bear on the bones adjoining the middle cuneiform when the weight of the user is applied to the fore part of the foot. 105

5. A foot exercising appliance comprising a base; two pairs of mounds rising from and fixedly mounted on the base, each pair being adapted to receive and support a human foot, the mounds of each pair being spaced from each other to respectively engage the arch and the metatarsal arch of the foot alternately when the user's weight is shifted from his toes to his heels in exercising; and means on the base beyond the mounds for engaging the toes and heels of the user's feet to support the latter in the terminal position of the weight shifting movements. 110

6. A foot exercising appliance comprising a base; and two pairs of mounds on the base, each pair being adapted to receive and support a human foot, the mounds of each pair being spaced from each other to respectively engage the arch and the metatarsal arch of the foot, the mounds being dome-shaped and being made of a resiliently displaceable material to spread under the user's weight and apply pressure on the overlying bones and simultaneously kneading the adjacent tissues and muscles. 115

7. A foot exercising appliance comprising a base; and two pairs of mounds on the base, each

pair being adapted to receive and support a human foot, the mounds of each pair being spaced from each other to respectively engage the arch and the metatarsal arch of the foot, one mound of each pair having a plug and a plurality of sockets in the base to receive the plug whereby the mound may be held in a variety of positions on the base to vary the distances between the mounds in each pair.

10 8. A foot exercising appliance comprising a base; and two pairs of mounds on the base, each pair being adapted to receive and support a human foot, the mounds of each pair being spaced from each other to respectively engage the arch and the metatarsal arch of the foot, at least one mound in each pair being made of sponge rubber 15 and having auxiliary means for increasing its resistance to compression.

9. A foot exercising appliance comprising a

20

base of sponge rubber on which the user stands and rocks forward and backward shifting his weight from one end of the foot to the other; sponge rubber mounds rising from and fixedly mounted on the base acting on the metatarsal 80 arches; and other and substantially larger sponge rubber mounds likewise rising from and fixedly mounted on the base acting on the arches, said mounds being narrower than the parts of the foot they respectively engage and thereby alternately 85 applying regional yielding pressure to the bones of the foot at the intersections of the metatarsal arch and the arch with the longitudinal axis of the foot as the user's weight is shifted and as a result of the deformation of said mounds when receiving the user's weight.
